UNITED STATES PATENT OFFICE

FRANK W. MERRICK, OF BOSTON, MASSACHUSETTS

LASTING AND FASTENING MACHINE

Application filed April 5, 1926. Serial No. 99,731.

The invention relates to machines for use in the manufacture of boots and shoes, and particularly to machines for performing lasting operations and conjointly therewith attaching the upper of a shoe to the sole. Specifically, it has relation to machines for performing the operations just mentioned in the case of shoes of the outturned-upper class, for instance the so-called stitch-down or 10 Veldtschoen type of shoes.

One general object of the invention is to provide a machine of novel and improved character for lasting a shoe of the class aforesaid and in addition fastening the loose outturned margin of the upper thereof to the sole-margin projecting beyond the last. Another, is to provide a machine for the said purpose operating upon a novel principle to automatically tighten the upper around the 20 top and side of the last so that it shall conform snugly thereto without any wrinkles or slack whatever. Another, is to provide a machine embodying the principle just mentioned and including means whereby, as the 25 operation of fastening the upper to the sole-margin proceeds, the upper-margin shall be moved along automatically at a manually-controllable rate, with capacity for a change in the differential rate relative to the sole so that in going around convexities of the last, as for example the fore-part and toe, any excess of the material of the upper-margin may be distributed between successive stitches or other fastenings, and thereby may be prevented from showing.

In accordance with one part of the invention, I provide, in combination with a work-rest for supporting for the lasting and fastening operations a last and shoe parts applied thereto, means by which the loose outspread margin of the upper is engaged at a short distance outward from the last and thereby held from movement toward the last-side, and means acting upon the upper at a point between the last-side and the said engaging and holding means to bend the intermediate portion of the upper toward the surface of the right side of the sole, thereby tightening the upper around the top and side 45 of the last; and I arrange fastening-applying

means in such relations that fastenings securing such bent portion of the upper to the said surface of the sole are applied along the crease of the upper.

Another part of the invention consists in 55 the embodiment of the said features in the organization of a combined lasting and sewing machine.

The foregoing, and certain additional 60 phases and features of the invention, are further specified in the claims at the close of this specification.

The drawings show an illustrative embodiment of the invention in the shape of a lasting and sewing machine, but only so much is 65 shown of the sewing mechanism and general machine as is required for an understanding of the nature of the invention.

In the drawings,—

Fig. 1 is a partly sectional elevation of certain of the parts of a combined lasting and fastening machine, illustrating those parts which are more immediately involved in the invention, together with certain associated portions of the machine, and showing also 75 portions of a last, upper, and sole which are being operated upon.

Fig. 2 is a plan view of the subject-matter that is shown in Fig. 1, but omitting the portions of last, upper, and sole. 80

Fig. 3 is an elevation of certain of the parts of Fig. 1 and 2, looking from the left hand side in the latter views.

Fig. 4 shows in side elevation the presser-foot of Figs. 1, 2 and 3, and Fig. 5 is a bottom view thereof. 85

Figs. 6 and 7, Sheet 2, are cross-sectional views illustrating the holding of the upper-margin and the tightening of the upper around the last. 90

Fig. 8, Sheet 3, is a plan view supplementing Fig. 2, illustrating the work-rest 6 and presser 7 at the end of their return stroke, and the supplemental presser 12 at the completion of the stroke which it makes in feeding the upper-margin along, the adjustment for length of stroke being the same as in Fig. 2. 95

Fig. 9, Sheet 3, is a plan view showing in full lines the work-rest and presser 7 at the end of their feeding stroke and the supple- 100

mental presser 12 at the starting point of its feeding stroke, with the actuating devices for supplemental presser 12 adjusted to give the maximum length of stroke to the supplemental presser. The dotted lines show the parts in the positions occupied by them at the conclusion of the feeding stroke of the supplemental presser.

Figs. 10 and 11, Sheet 3, are detail views on an enlarged scale showing a minimum feed-movement of the supplemental presser, and Figs. 12 and 13 are views similar to Figs. 10 and 11, but illustrating the parts in the same positions as in full lines and dotted lines, respectively, Fig. 9, for a long feed-movement.

Fig. 14, Sheet 2, is a plan view illustrating the effect of movement of the upper-margin engaging and holding device from the position thereof shown in Fig. 10 to the position shown in Fig. 11.

Fig. 15 is a plan view, similar to Fig. 9, but showing a modification.

Having reference to the drawings:

25 Figs. 6 and 7 illustrate the chief characteristic feature of a shoe of the outturned-upper class, namely the outturned marginal portion, 100, of the upper 10, resting upon the right side of the outstanding marginal portion of the sole 9. By "right side" I intend that surface of the sole which is uppermost in a shoe as the latter is worn, as contradistinguished from the tread surface. In practice, the upper and sole of a shoe of such 30 class are connected together by means of fastenings engaging with the said outturned or outstanding marginal portions. These fastenings may vary in character but usually consist of stitches, as at 11, Figs. 6 and 7. 35 Only a so-called inner seam is shown in the drawings, but usually the fastenings comprise an inner seam (shown) and an outer seam (not shown) that is applied subsequently.

40 45 The machine that is partly shown in the drawings is one intended to apply fastenings constituted by stitches 11. The stitching devices include an awl 1, carried by a vertically reciprocating awl-bar 2; also a straight needle 3, Figs. 1, 2, 3, 6, and 7, carried by a vertically reciprocating needle-bar 4 which works in guides in connection with a needle-post 5; and also, in the case of the complete machine, the usual parts cooperating with the 50 needle in the formation of stitches.

55 The said machine is equipped with a work-rest 6 serving also as an under-clamp, and with a work-presser, or presser-foot, 7, cooperating in usual manner with the awl and needle in the stitch-forming operations, etc.

60 As thus far referred to the said parts, and other parts (not shown) which are associated therewith in practice, are or may be, excepting as pointed out hereinafter, the same as 65 in the machine shown and described in U. S.

Letters Patent for improvement in sewing machines, No. 1,077,625, granted under date of Nov. 4, 1913. The needle-post 5 is fixed or stationary, while the under-clamp or work-rest 6, the presser 7, and the awl-bar and awl, have feed-movements in the line of the feed; and the presser automatically is raised from the work at the completion of every advancing movement and following its return to the starting point is caused to descend into engagement with the work again.

65 After the sole 9 and upper 10 of a shoe of the outturned-upper class have been assembled in connection with a last 8, the loose upper-margin, prior to being fastened to the outstanding sole-margin, stands out more or less from the last-side, over the said outstanding sole-margin; that is to say, it extends from the top of the last obliquely outward and downward to the outer portion of the sole-margin, somewhat as at the right hand side of Fig. 6. The devices shown herein embodying the principles of the invention utilize this outspread condition of the loose upper-margin.

70 In the use of the mechanism shown in the drawings, the assembled last, sole, and upper are applied to the machine while presser 7 occupies an elevated position as in Fig. 6. 75 As applied, the tread-surface of the project-thickness of upper are in contact with the work-rest 6, the last-side and interposed outer side of presser 7, and the projecting sole-margin and the obliquely outspread loose margin of the upper occupy positions between the presser and the work-rest and extend somewhat beyond the presser at the side of the presser opposite that at which the last is located.

80 In the drawings the means by which, after a last and associated shoe-parts have been applied to the machine as in Fig. 6, the loose outspread margin of the upper is engaged at a short distance outward from the last, 85 and thereby held from movement toward the last-side, is a supplemental presser 12. The said supplemental presser is located at the opposite side of the awl 1, presser 7, and needle 3, from that at which the last is held. 90 The operation of placing the last and shoe-parts in position as just described is performed when the said supplemental presser 12, (like presser 7), occupies an elevated position so that as the outstanding margins 95 of the sole and upper are passed in under the upraised presser 7 they may pass in under the upraised supplemental presser 12 too. By descent of the supplemental presser the outstanding loose margin of the upper is 100 clamped by the supplemental presser, as in Fig. 6, against the surface of the right side of the sole-margin.

105 To provide for clamping and unclamping movement of the supplemental presser 12 it 110

is constituted by the free extremity of one arm, 121, of a lever which is mounted pivotally by means of center-screws 122, 122, upon a supporting carrier 14, with capacity to swing relative to such carrier in a vertical or up-and-down direction around a horizontal axis extending lengthwise of the said screws. To actuate the supplemental presser yieldingly toward the surface of work-rest 6, to engage the loose margin of the upper and temporarily hold such margin pressed firmly against the surface of the right side of the projecting sole-margin, as in Figs. 1, 6, and 7, the tail 123 of the presser-lever has combined therewith a spring 124, the tension of which operates to produce such clamping movement and holding action. The spring 124 is shown confined between the said tail 123 and a portion of the supporting carrier 14 for the presser-lever. In the regular working of the machine reverse or unclamping movement of the presser in opposition to the spring is produced automatically, in this instance, by means of nuts 125, Figs. 1 and 2, upon the upper threaded end of a rod 126 extending through a hole in the tail 123 of the supplemental presser, the lower end of such rod being connected with an arm 127 fixed upon a rockshaft 129. By movement of the rod 126 and nuts 125 in one direction the pressure of the nuts against the tail 123 is relieved and closing movement of the supplemental presser 12 under the action of the spring 124 is permitted. Movement of the rod 126 in the opposite direction causes the nuts 125 to act against the tail 123 so as to open the supplemental presser away from the upper and sole-margins and thereby unclamp the said margins. To provide for manual lifting of the supplemental presser, when required, a wire 13 is engaged with the arm 121. Such wire in practice is connected with any conveniently disposed lever, treadle, or the like.

In the working of the mechanism, the presser 7 remains lifted until after the closing movement of the supplemental presser has taken place. In virtue of presser 7 remaining lifted for the time being, it follows, inasmuch as the supplemental presser in closing toward the work-rest or clamp 6 takes hold of the free margin of a portion of the upper that spreads out laterally from the last-side, at the side of the awl and needle, opposite that at which the last is situated, that a portion of the upper which is intermediate the last-side and the supplemental presser continues to extend obliquely outward as in Fig. 6, from the last-side to the point at which the margin is clamped against the surface of the right side of the projecting sole-margin by the supplemental presser.

Following the completion of the closing movement of the supplemental presser, and while such presser is holding the outer por-

tion of the margin of the upper firmly in contact with the surface of the right side of the projecting sole-margin as in Fig. 6, the descent of the uplifted presser 7 from its position in Fig. 6 to that occupied by it in Fig. 7 takes place in the regular working of the stitching mechanism. In thus descending the presser 7 acts, nearer the last-side, that is to say between the point at which such pressure and contact are maintained by the supplemental presser, and the adjoining last-side, upon the portion of upper extending obliquely outward from the last to the sole in Fig. 6, and bends such portion against the sole close to such side of the last, as in Figs. 1 and 7. In doing so it tightens and smooths the upper around the said side and the top of the last.

The awl 1 and needle 3 work closely alongside the last, through a slot 71, Figs. 4 and 5, in the presser 7, in the operations by which the fastening stitches 11 are produced, thereby providing for applying such stitches to the margins of the upper and sole between the last-side and the clamping and holding means 12. To provide for supporting the last and applied shoe-parts in proper position enabling such stitches to be applied close in under the last-side at the bottom of the last, in what is called the crease, and also for enabling the stitches to pass through the upper and the sole with an inclination inward toward the center of the last, I dispose the work-supporting top of the work-rest or lower clamp-member 6 at an angle to the line of reciprocation of the awl and needle, as illustrated in Figs. 1, 6, and 7, with the portion thereof which is located at the rear side of the awl and needle (the right hand side in the drawings) higher than that portion which is located at the front side (the left hand side in the drawings). Through this inclination of the top of the work-rest, a last and shoe-parts applied thereto are supported for the lasting and fastening-applying operations with the plane of the sole at an inclination presenting the last at one side of and clear of the path of the awl and needle, while the apex of the entrant angle between the last-side and the projecting margin of the sole into which the portion of upper intermediate the upper and the engaging and holding means 12 is bent by presser 7 in its reciprocating movements, is located substantially in the said path.

As will be perceived in Figs. 6 and 7, the wall 72 of slot 71 in presser 7, located at the side of the presser at which the last and enclosing upper are presented, constitutes a guard for the upper by which injury to an adjoining upstanding portion of the upper by either the awl or the needle is prevented. The lower portion of the said guard wall is removed as at 73, Fig. 4, to permit the lower part of the last-side and the portion of upper

covering it to be carried in close to the paths of the said tools, as indicated in Figs. 6 and 7. The presser 7 is formed with a narrow working edge, 74, substantially in line with the work-penetration tools 1 and 3, in order that as the presser approaches the sole, the presser may act the more efficiently in forming a sharply defined bend in the upper and crowding it into the angle between the last-side and the outstanding margin of the sole, and in order that said tools may penetrate the said bend and sole in line with said working edge.

The usual feed-movements of the work-rest or under-clamp 6, presser 7, and awl are coordinated with the stitch-forming operations as heretofore, so that as successive stitches are formed the last and applied shoe-parts are fed along.

In practice, satisfactory results can be secured with the parts as thus far described, provided the operator makes by hand suitable adjustment of the loose margin of the upper to distribute fulness of the upper around convexities of the last so as to be taken up properly by the successive stitches as they are formed. However, the invention in its more complete embodiment provides for moving the upper-margin along automatically at a manually-controllable rate, so that, as referred to at the outset in this specification, in going around convexities of the last, as for example the fore-part and toe, any excess of the material of the upper-margin may be distributed between successive stitches and thereby may be prevented from showing. To this end, accordingly, I combine with the supplemental presser 12 means for producing feed-movements thereof. Thereby, a feed-movement of the supplemental presser 12 is caused to take place while the said presser continues to hold the margin of the upper firmly against the margin of the sole. This feed-movement is provided for by mounting the supporting carrier, 14, for the supplemental presser 12 with capacity for swinging movement in the direction of the feed. The said carrier is shown supported by a fixed plate 15 at the top of a fixed support 151, Fig. 1, and as having a vertical pivot 141, around the axis of which it is adapted to swing. The required swinging movement is imparted to the carrier 14 through actuating devices comprising a link 142 connecting the carrier to one arm, 143, of a lever working around a vertical pivot 144 and having a second arm, 145, thereof engaged by a loose-joint connection, 146, with an arm, 1291, Figs. 1 and 2, of a rockshaft 1292. Through the devices referred to, the supplemental presser is given feed-movements in the direction of the feed, and return-movements, in proper sequence with the corresponding movements of the work-rest or under-clamp, presser 7, etc.

In the case of the illustrated machine, the feed-movements and return-movements to starting position of the supplemental presser 12 alternate with those of the work-rest 6, presser 7, and awl. The cycle is as follows: Let it be assumed that the work-rest 6, presser 7, and awl have just completed an advancing feed-movement and for the moment occupy the relation to needle 3 corresponding with that shown in Fig. 2 in the case of the work-rest and said presser. At this moment the supplemental presser 12 is at the starting point in its feed-stroke, as indicated in Fig. 2. Supplemental presser 12 closes down on the extended loose upper-margin, clamping it against the surface of the right side of the projecting sole-margin. The needle being engaged with the sole and upper margins, the presser 7 lifts and it and the awl and work-rest move to starting position, shown in Fig. 8, while concurrently therewith supplemental presser 12 is given its feed-movement to its relative position shown in Fig. 8, whereby the upper-margin is carried forward against the needle-stem, fulling-up to a greater or less extent against the said stem, as indicated in Fig. 14. The presser 7 now descends upon the upper-margin, thereby grasping the fulness and retaining it, the needle withdraws, the stitch is completed, the awl enters the upper and sole-margins in advance of the fulness held by the two pressers, the supplemental presser 12 rises, and as the ensuing feed-movements of the work-rest 6, presser 7, and awl 1, take place the supplemental presser 12 returns to starting position.

To enable the extent of the feed-movements of the supplemental presser to be regulated, the link 142 is connected with the arm 143 of the motion transmitting lever in manner providing for adjustment of the point of connection inward and outward of the said arm, that is to say, toward and from the pivotal axis of the said lever. In this instance, the link 142 carries a small block 1422 that is slotted to fit upon the arm 143, and adjustment is effected by swinging the link and thereby sliding the block upon the arm. The arm 143 is curved so as to be concentric with the pivot connecting the opposite end of link 142 with carrier 14, in order that the feed-movements of the supplemental presser 12 may end up in the same relation to needle 3 under all adjustments of the link along the arm 143. The effect of such adjustments is to vary the length of the said feed-movements by increasing or decreasing the length of the return strokes of such presser and thereby advancing the starting point, or the reverse.

For the purpose of enabling the adjustment of link 142 along arm 143 to be effected conveniently, especially while the mechanism is in operation, the link 142 has its end thereof adjacent the arm 143 joined by a link, 16,

with one arm of a bell-crank 161, mounted pivotally upon the machine frame at 162, and having engaged with its other arm a connection 163, Figs. 1 and 3, extending to any approved device through which manual 5 actuation of the parts may be effected for the purposes of the desired adjustment. The link-adjustment shown in Fig. 2 corresponds with a short, but not the shortest, feed-movement of the supplemental presser. Through 10 adjustment of the link to a position on arm 143 closer to the axis of pivot 144, the return-stroke of the supplemental presser 12 may be shortened to give the said part the starting position indicated in Fig. 10, so that in moving 15 from its position in Fig. 10 to that in Fig. 11, (which last shows the supplemental presser at the end of its minimized feed-stroke) the effect in feeding the upper-margin relative to the sole-margin will be minimized. Through adjustment of the link to the outer end of arm 143 as in Fig. 9, the return-stroke of supplemental presser 12 may be extended so as to give such part the starting point indicated in Figs. 9 and 12, with 20 the increase in the feed-movement that is apparent upon comparing Fig. 12 with Fig. 13, which last shows the supplemental presser at the end of its feed-stroke.

By reason of the adjustability which has just been described, and of the resulting capacity for regulation of the working of the devices for imparting feed-movements to the supplemental clamp 12, such feed-movements 30 may be regulated to bear any desired relation or ratio with respect to the feed-movements of the work-rest or lower clamp 6, presser 7, and awl. That is to say, the feed-movements of the supplemental clamp may be made to correspond closely in extent with those of the other parts named, in order thereby to feed the upper-margin along at substantially the same rate as the sole-margin, or, they may be caused to vary in extent 40 therefrom, in order to attain any desired difference in the rate of feed of the two. For example, to the supplemental clamp may be given any desired relatively greater extent of feed-movement within the capacity of the 45 construction in going around convexities of the last, as, for instance around the fore-part and toe, so as to distribute any excess of the material of the upper-margin between successive stitches or other fastenings, and 50 thereby such excess may be prevented from showing in the form of wrinkles or unrequired fulness in the finished shoe. For convenience and compactness of expression, the devices just described may be styled herein 55 means for actuating the supplemental presser-member to move the upper-margin along at a manually-controllable rate, with capacity 60 for a change in the differential rate with respect to the work-feed.

Should, for any reason, it be deemed neces-

sary to provide for a negative or reverse feed of the upper-margin taking place at times; the lever-arm with which the transmitting link is adjustably engaged may be formed to extend at both sides of the pivotal axis of 70 the transmitting lever. Thus, in Fig. 15, the lever-arm 1431 is thus formed with relation to the pivotal axis 144, so that the link, 1421, in addition to adjustments upon said lever-arm at one side of said pivotal axis for the 75 attainment of the results indicated by Figs. 2 and 8 to 13, may be adjusted to the opposite side of such pivotal axis by shifting to the said opposite side the block 1423 by means of which the link is connected to the lever-arm, 80 as shown in Fig. 15. Thereby the supplemental clamp, while closed upon the upper-margin, will be actuated to feed the latter reversely with respect to the feed produced by the feed-movement of the work-rest 6, 85 presser 7, and awl.

To enable the operator conveniently to manipulate the upper-margin in relation to the presser 7, and supplemental presser 12, during the performance of the lasting and fastening operations, the arm 121 is recurved, as shown, intermediate such parts and the pivotal support 141, which last is laterally removed from the work-rest and the said pressers. Thereby a clear unobstructed opening 95 is provided alongside the said parts to accommodate the operator's hand employed for such manipulation.

The pivotal point 141 around which supplemental presser 12 swings is located a little 100 forward relative to the said presser, so that the arc in which the latter swings is directed somewhat obliquely away from the last, awl, needle, and work-rest. Consequently, as the supplemental presser moves toward starting position it approaches the last slightly, and in its feed-movement it separates slightly from the last. In thus separating from the last while maintaining its clamping pressure upon the upper-margin, the supplemental presser 105 tends to stretch the loose margin of the upper away from the last-side, thereby increasing the effect in smoothing the upper upon the last.

Various changes in construction, etc., and in the precise manner of applying the main principles and features of the invention, may be made in practice. While herein the needle does not participate in the feed-movements, the main features of the invention are equally 115 applicable to a machine of one of the known types in which the needle does participate in the feed-movements while the awl does not. In part, also, the said main features are applicable in a machine of one of the known 120 types in which the work-rest does not participate in the feed-movements.

What is claimed as the invention is:—

1. A lasting and fastening machine having 130 means for supporting for the lasting opera-

tion a last and shoe-parts applied thereto, means by which the outstanding margin of the upper is engaged at a short distance outward from the last and held from movement toward the last, means operating to tighten the upper around the top and side of the last through acting upon the upper at a point intermediate the last-side and the said engaging means to bend the intermediate portion of the upper toward the sole, means for applying between the last-side and the engaging and holding means fastenings securing such bent portion of the upper to the sole in the angle alongside the last, and means for feeding the last and shoe for repetitions of the respective operations.

2. A lasting and fastening machine having means for supporting for the lasting operation a last and shoe-parts applied thereto, means by which the outstanding margin of the upper is engaged at a short distance away from the last and held from movement toward the last, means acting upon the intermediate portion of upper at a point between the last-side and the engaging means and bending such intermediate portion toward the sole, thereby tightening the upper around the top and side of the last, and stitch-forming mechanism which fastens the thus bent portion of the upper to the sole by stitches between the side of the last and the engaging means, such mechanism feeding the lasted shoe progressively while successive stitches are formed.

3. A lasting and fastening machine having means for supporting for the lasting operation a last and shoe-parts applied thereto, means by which the outstanding margin of the upper is engaged at a short distance outward from the last and held from movement toward the last, stitching mechanism having a presser which reciprocates toward and from the plane of the sole between the side of the last and such engaging means and in approaching the sole bends the intermediate portion of upper toward the sole, thereby tightening the upper around the top and side of the last, and stitch-forming devices by which the thus bent portion of the upper is fastened to the sole by stitches between the side of the last and the said engaging means.

4. A lasting and fastening machine having means for supporting for the lasting operation a last and shoe-parts applied thereto, a presser device which engages the outstanding margin of the upper at a short distance from the last and holds such margin from movement toward the last-side, means for acting between the last-side and said device upon the intermediate portion of upper and bending such portion toward the sole, thereby tightening the upper around the top and side of the last, means for applying fastening devices securing such bent portion of the upper to the sole between the last and the

said device, and means for feeding the last and shoe for repetitions of the respective operations.

5. A lasting and fastening machine having means for supporting for the lasting operation a last and shoe-parts applied thereto, an engaging device which engages the outstanding margin of the upper at a short distance from the last and holds such margin from movement toward the last-side, a presser which reciprocates toward and from the plane of the sole between the last-side and the said device and in approaching the sole bends toward the sole the intermediate portion of upper, thereby tightening the upper around the top and side of the last, and stitch-forming mechanism which fastens the thus bent portion of the upper to the sole by stitches between the side of the last and the said device.

6. A lasting and fastening machine having means for supporting for the lasting operation a last and shoe-parts applied thereto, a presser device which engages the outstanding margin of the upper at a short distance from the last and holds such margin from movement toward the last-side, a presser which reciprocates toward and from the plane of the sole between the last-side and the said device and in approaching the sole bends toward the sole the intermediate portion of upper, thereby tightening the upper around the top and side of the last, and stitch-forming mechanism which fastens the thus bent portion of the upper to the sole by stitches between the side of the last and the said device.

7. A lasting and fastening machine having means for supporting for the lasting operation a last and shoe-parts applied thereto, an engaging device which engages the outstanding margin of the upper at a short distance from the last and holds such margin from movement toward the last-side, a presser which reciprocates toward and from the plane of the sole between the last-side and the said device and in approaching the sole bends toward the sole the intermediate portion of upper, thereby tightening the upper around the top and side of the last, and a stitch-forming mechanism which fastens the thus bent portion of the upper to the sole by stitches between the side of the last and the said device, such mechanism having provisions for feeding the lasted shoe progressively while successive stitches are formed.

8. A lasting and fastening machine having means for supporting for the lasting operation a last and shoe-parts applied thereto, a presser device which engages the outstanding margin of the upper at a short distance from the last and holds such margin from movement toward the last-side, a presser which reciprocates toward and from the plane of the sole between the last-side and

the said device and in approaching the sole bends toward the sole the intermediate portion of upper, thereby tightening the upper around the top and side of the last, and 5 stitch-forming mechanism which fastens the thus bent portion of the upper to the sole by stitches between the side of the last and the said device, such mechanism having provisions for feeding the lasted shoe progressively while successive stitches are formed.

10 9. A lasting and fastening machine having stitch-forming devices, a work-rest inclined upward and rearward to a degree presenting the side of a last in front of and clear of the path of the needle of said devices, 15 with the angle between the said side and the projecting margin of the sole of a shoe approximately in such path, and a presser reciprocating toward and from the plane of the sole and operating to work an upper into an angular formation between the last-side 20 and the said projecting sole-margin, thereby enabling the upper to be fastened very close to and held in the crease of the upper.

25 10. A lasting and fastening machine having stitch-forming devices including a straight needle, a work-rest inclined upward with relation to the needle path to a degree presenting the apex of the angle between the 30 side of a last and the sole substantially in said path, with the said side at one side thereof, and a presser reciprocating parallel with the needle into said angle and thereby working the upper into the said apex.

35 11. A lasting and fastening machine having stitch-forming devices including a straight awl and a straight needle, means by which a last and shoe-parts applied thereto are supported for the lasting and fastening 40 applying operations with the plane of the sole at an inclination presenting the last at one side of and clear of the path of the said awl and needle, and with the apex of the entrant angle between the last-side and the projecting margin of the sole substantially in the 45 said path, means by which the outstanding margin of the upper is engaged at a short distance from the last and thereby held from movement toward the last, and a reciprocating presser by which the portion of upper intermediate the last and the said engaging and holding means is bent into the said angle to receive the stitches, thereby also tightening the upper around the top and side of the 50 last.

55 12. A lasting and fastening machine having a work-rest and a presser, one thereof arranged to force the upper into the angle between the side of the last and the projecting 60 margin of the sole, said work-rest being adapted to support work comprising a last and shoe-parts applied thereto, stitching devices acting to form in the said angle stitches fastening the upper and sole together, such 65 devices acting also to feed the work along,

and means for holding the free margin of the upper from movement toward the last while the intermediate portion of the upper is being forced into the angle aforesaid, and feeding the said margin at a manually controllable rate with capacity for a change in the differential rate relative to the feed by the stitching devices.

70 13. A lasting and fastening machine having means for supporting for the lasting operation work comprising a last and shoe-parts applied thereto, a holding device by which the outstanding margin of the upper is engaged at a short distance outward from the last and prevented from movement toward the last, means acting upon the upper between the last-side and the said holding device to bend the intermediate portion of the upper toward the sole and thereby tighten the upper around the top and side of the last, 75 means for applying alongside the last fastenings securing such bent portion of the upper to the sole and feeding the work progressively, and means actuating said holding device to move the upper-margin along at a manually controllable rate with capacity for a change in the differential rate relative to the work-feed.

80 14. A lasting and fastening machine having means for supporting for the lasting operation work comprising a last and shoe-parts applied thereto, a holding device by which the outstanding margin of the upper is engaged at a short distance outward from the last and prevented from movement toward the last, means acting upon the upper between the last-side and the said holding device to bend the intermediate portion of the upper toward the sole and thereby tighten the upper around the top and side of the last, 85 means for applying alongside the last fastenings securing such bent portion of the upper to the sole and feeding the work progressively, and means actuating said holding device to move the upper-margin along at a manually controllable rate with capacity for a change in the differential rate relative to the work-feed.

90 15. A lasting and fastening machine having means for supporting for the lasting operation work comprising a last and shoe-parts applied thereto, a holding device by which the outstanding margin of the upper is engaged at a short distance outward from the last and prevented from movement toward the last, means acting upon the upper between the last-side and the said holding device to bend the intermediate portion of the upper toward the sole and thereby force the 95 said portion into the angle between the last-side and the projecting margin of the sole, means for applying in the said angle fastenings securing the upper and sole together and for feeding the work along, and means actuating said holding device to move the upper- 100

105 110 115 120 125 130

margin along at a manually controllable rate with capacity for a change in the differential rate relative to the work-feed.

16. A lasting and fastening machine having means for supporting for the lasting operation work comprising a last and shoe-parts applied thereto, a holding device by which the outstanding margin of the upper is engaged at a short distance outward from the last and prevented from movement toward the last, means acting upon the upper between the last-side and the said holding device to bend the intermediate portion of the upper toward the sole and force the said portion into the angle between the last-side and the projecting margin of the sole, stitch-forming means which fastens the thus bent portion of the sole by stitches in the apex of the said angle and feeds the work along progressively, and means actuating said holding device to move the upper-margin along at a manually controllable rate with capacity for a change in the differential rate relative to the work-feed.

17. A lasting and fastening machine having means for supporting for the lasting operation work comprising a last and shoe-parts applied thereto, a holding device by which the outstanding margin of the upper is engaged at a short distance outward from the last and thereby held from movement toward the last, a reciprocating presser which bends toward the sole the portion of upper intermediate the last-side and the said holding device and forces the said portion into the angle between the last-side and the projecting margin of the sole, stitch-forming means which fastens the thus bent portion of the sole by stitches in the apex of the said angle and feeds the work along progressively, and means actuating said holding device to move the upper-margin along at a manually controllable rate with capacity for a change in the differential rate relative to the work-feed.

18. A lasting and fastening machine having stitch-forming devices including a straight needle, means by which work comprising a last and shoe-parts applied thereto is supported for the lasting operation with the plane of the sole at an inclination presenting the side of the last at one side of and clear of the path of the said needle, while the apex of the entrant angle between the said side and the projecting margin of the sole is located substantially in said path, a holding device by which the outstanding margin of the upper is engaged at a short distance outward from the last and held from movement toward the last, means for bending toward the sole the portion of upper intermediate the last-side and the said holding device and forcing the said portion into the said angle, the said stitch-forming devices being arranged to fasten the thus bent portion of the

sole by stitches in the said apex, and feed the work along progressively, and means actuating said holding device to move the upper-margin along at a manually controllable rate with capacity for a change in the differential rate relative to the work-feed.

19. A lasting and fastening machine having stitch-forming devices including a straight needle, means by which work comprising a last and shoe-parts applied thereto is supported for the lasting operation with the plane of the sole at an inclination presenting the side of the last at one side of and clear of the path of the said needle, while the apex of the entrant angle between the said side and the projecting margin of the sole is located substantially in said path, a holding device by which the outstanding margin of the upper is engaged at a short distance outward from the last and held from movement toward the last, a presser which reciprocates toward and from the plane of the sole and said holding device and in approaching the sole bends the intermediate portion of the upper toward the sole, in addition crowding the bent portion into the said apex, the said stitch-forming devices being arranged to fasten the thus bent portion of the sole by stitches in the said apex, and feed the work along progressively, and means actuating said holding device to move the upper-margin along at a manually controllable rate with capacity for a change in the differential rate relative to the work-feed.

20. A lasting and fastening machine having a work-rest for supporting for the lasting operation work comprising a last and shoe-parts applied thereto, a presser-member by which the outstanding margin of the upper is clamped between such member and the sole where backed-up by the work-rest so that the said margin thereby is held from movement toward the last-side, means for acting upon the portion of upper intermediate the presser-member and the last-side and bending such portion toward the sole, thereby tightening the upper around the top and side of the last, devices for applying alongside the last fastenings securing such bent portion of the upper to the sole and for feeding the work along, and means for actuating said presser-member to move the upper-margin along at a manually controllable rate with capacity for a change in the differential rate with respect to the work-feed.

21. A lasting and fastening machine having a work-rest for supporting for the lasting operation work comprising a last and shoe-parts applied thereto, a supplemental presser-member by which the outstanding margin of the upper is clamped against the sole where the latter is backed-up by the work-rest so that the said margin thereby is held from movement toward the last-side, a presser which reciprocates toward and from the plane

of the sole between the last-side and the supplemental presser and in approaching the sole bends toward the sole the intermediate portion of upper, thereby tightening the upper around the top and side of the last, devices for applying alongside the last fastenings securing such bent portion of the upper to the sole and for feeding the work along, and means for actuating said presser-member

10 to move the upper-margin along at a manually controllable rate with capacity for a change in the differential rate with respect to the work-feed.

22. A lasting and fastening machine having stitch-forming and work-feeding devices including a straight needle, a work-rest by which work comprising a last and shoe-parts applied thereto is supported for the lasting operation with the plane of the sole at an 15 inclination presenting the last-side at one side of and clear of the path of said needle while the apex of the entrant angle between the last-side and the projecting margin of the sole is located substantially in said path, 20 a supplemental presser-member by which the said margin is clamped against the sole-margin so that the said margin is held from movement toward the last-side, a presser which reciprocates toward and from the 25 plane of the sole between the last-side and the supplemental presser and in approaching the sole bends toward the sole the intermediate portion of upper, thereby tightening the upper around the top and side of the last, and 30 means for actuating said supplemental presser member to move the upper-margin along at a manually controllable rate with capacity for a change in the differential rate with respect to the work-feed.

40 23. A lasting and fastening machine having means for supporting for the lasting operation a last and shoe-parts applied thereto, stitch-forming devices including a work-penetrating tool, means by which the outstanding margin of the upper is engaged at a short distance from the last and thereby held from movement toward the last, a presser which reciprocates parallel with the work penetrating tool of the stitch-forming devices toward and from the plane of the sole 45 between the last-side and the engaging and holding means, and enters into the angle between the side of the last and the sole having a narrow working edge which as the presser 50 approaches the sole bends the intermediate portion of upper toward the sole, thereby tightening the upper around the top and side of the last and crowding the bend into the angle between the last-side and the outstanding margin of the sole, the stitch-forming devices having the work penetrating tool thereof arranged to penetrate the said bend and the sole in line with the said working edge.

55 24. A lasting and fastening machine

having means for supporting for the lasting operation a last and shoe-parts applied thereto, means for applying fastenings which secure the upper to the sole along the side of the last, work-feeding means, a member arranged to engage the upper-margin adjacent the point at which the fastenings are applied, means actuating said member to move along with the upper-margin at a manually controllable rate with capacity for a change in its rate of feed relative to the work-feed, and means providing a pivotal mounting for said member which is laterally removed from the supporting and fastening applying means, 70 said member having a supporting arm which is recurved intermediate the pivotal axis and said supporting and fastening means, with a clear unobstructed opening alongside the latter to accommodate the operator's hand employed for manipulating the upper-margin during the lasting and fastening operations.

25. A lasting and fastening machine having means for supporting for the lasting operation a last and shoe-parts applied thereto, 75 means for applying fastenings which secure the upper to the sole along the side of the last, work-feeding means, a member arranged to engage the upper-margin adjacent the point at which the fastenings are applied, means actuating said member to move along with the upper-margin at a manually controllable rate with capacity for adjustment of its rate of feed relative to the work-feed, and means providing a pivotal mounting for 80 said member, such means being arranged for operation of said member closely alongside the fastening applying means, with a clear open space adjoining such member to admit the operator's hand to permit manipulation of the upper-margin during the lasting and fastening operations.

26. A lasting and sewing machine having a work-rest for supporting for the lasting operation a last and shoe-parts applied thereto, a presser which reciprocates toward and from the work-rest, an awl, and a needle, the said work-rest, presser, and awl moving in unison for feeding the last and shoe-parts along during the stitching process and comprising the main work-feed, and having in combination with the said elements a member for engagement with the outstanding margin of the upper, and means for actuating said member to engage with the said margin at a short distance outward from the last, hold such margin from movement toward the last while the presser descends upon the upper between the member and the last and bends the upper into the angle between the last-side and the outstanding margin of the sole, and feed the upper-margin forward at a manually controllable rate with capacity for adjustment of its rate of feed relative to the main work-feed.

27. A lasting and sewing machine having a work-rest for supporting for the lasting operation a last and shoe-parts applied thereto, a presser which reciprocates toward and from the work-rest, an awl, and a needle, the said work-rest, presser, and awl moving in unison for feeding the last and shoe-parts along during the stitching process and comprising the main work-feed, and having combined with the said elements a supplementary presser and means for actuating such supplementary presser to press upon the outstanding margin of the upper at a short distance outward from the last, hold such margin from movement toward the last while the presser descends upon the upper between the supplementary presser and the last-side and bends the upper into the angle between the last-side and the outstanding margin of the sole, and feed the upper-margin forward at a manually controllable rate with capacity for a change in its rate of feed relative to the main work-feed.

28. A lasting and sewing machine having means for supporting for the lasting operation a last and shoe-parts applied thereto, and stitching mechanism including a needle and awl, such mechanism including also a presser which during the stitching operations reciprocates toward and from said supporting means, and having combined with the said elements a member which engages with the margin of the upper and carries it forward beneath the upraised presser, fulling it against the needle so that the fulness is grasped by the descending presser and retained by the latter beyond the awl as the latter performs its penetrating stroke.

29. A lasting and sewing machine having means for supporting for the lasting operation a last and shoe-parts applied thereto, and stitching mechanism including a needle and awl, such mechanism including also a presser which during the stitching operations reciprocates toward and from said supporting means, and having combined with the said elements a member which engages with the margin of the upper, effects a feed of such margin beneath the upraised presser and relative to the withdrawn awl while the needle is in the stock, and holds the thus fed portion of the upper-margin until such portion is engaged by the presser and awl.

30. A lasting and fastening machine having means for supporting for the lasting operation work comprising a last and shoe-parts applied thereto, stitching devices for uniting the upper to the sole by stitches in the angle between the last-side and the outstanding marginal portion of the sole, a member which engages the outstanding upper-margin and prevents it from moving toward the last, means actuating said member to move inward toward the last, engage with the upper-margin and then move in the direc-

tion of the feed as well as outward from the last, and a presser reciprocating toward and from the plane of the sole and in its movement toward such plane acting upon the upper between the last-side and the said member, thereby tightening the upper around the top and side of the last.

31. A lasting and fastening machine having means for supporting for the lasting operation a last having applied thereto a sole and an upper with outturned loose margin, a pressure which clamps the loose margin of the upper against the surface of the projecting sole-margin at a short distance from the last, a second presser which acts nearer the last-side to bend against said surface the intermediate portion of upper extending obliquely from the last to the presser first mentioned, both of said pressers having feed-movements, and means for securing the bent portion of the upper by fastenings applied to the sole alongside the last.

32. A lasting and fastening machine having means for supporting, right side up, for the lasting operation a last having applied thereto a sole and an upper with outturned loose margin, a presser which clamps the loose margin of the upper against the surface of the projecting sole-margin at a short distance from the last, a second presser which acts nearer the last-side to bend against said surface the intermediate portion of upper extending obliquely outward from the last to the presser first mentioned, both of said pressers having feed-movement, and means for securing the bent portion of the upper by fastenings applied to the sole alongside the last.

33. A lasting and fastening machine having means for supporting for the lasting operation a last having applied thereto a sole and an upper with outturned loose margin, a presser which clamps the loose margin of the upper against the surface of the projecting sole-margin at a short distance from the last, a second presser which acts nearer the last-side to bend against said surface the intermediate portion of upper extending obliquely from the last to the pressure first mentioned, both of said pressers having feed-movement, that of the first presser differentially proportioned with respect to the rate at which the last and shoe-parts are fed along, to dispose of excess fulness of the upper, and means for securing the bent portion of the upper by fastenings applied to the sole alongside the last.

34. A lasting and fastening machine having means for supporting, right side up, for the lasting operation a last having applied thereto a sole and an upper with outturned loose margin, a presser which clamps the loose margin of the upper against the surface of the projecting sole-margin at a short distance from the last, a second presser which

acts nearer the last-side to bend against said surface the intermediate portion of upper extending obliquely outward from the last to the presser first mentioned, both of said pressers having feed-movement, that of the first presser differentially proportioned with respect to the rate at which the last and shoe-parts are fed along, to dispose of excess fulness of the upper, and means for securing the bent portion of the upper by fastenings applied to the sole alongside the last.

35. A lasting and fastening machine comprising a work-rest for supporting a last and shoe-parts applied thereto, a supplemental presser by which the outstanding loose margin of the upper is engaged at a short distance outward from the last-side and whereby such margin is held from movement toward the last-side, a presser reciprocating toward and from the plane of the sole between the last-side and the supplemental presser and in approaching the sole operating to tighten the upper around the top and side of the last through bending the intermediate portion of the upper toward the sole, an awl and a needle penetrating the sole and the upper between the said supplemental presser and the last-side in stitch-forming operations by which fastening stitches are formed close alongside the last, said work-rest, presser, and one of the penetrating implements having work-feeding movements in unison and said supplemental presser having upper-margin feed-movements taking place during the return movements of the presser.

36. A lasting and fastening machine comprising a work-rest for supporting a last and shoe-parts applied thereto, a supplemental presser by which the outstanding loose margin of the upper is engaged at a short distance outward from the last-side and whereby such margin is held from movement toward the last-side, a presser reciprocating toward and from the plane of the sole between the last-side and the supplemental presser and in approaching the sole operating to tighten the upper around the top and side of the last through bending the intermediate portion of the upper toward the sole, an awl and a needle penetrating the sole and the upper between the said supplemental presser and the last-side in stitch-forming operations by which fastening stitches are formed close alongside the last, said work-rest, presser, and awl having work-feeding movements in unison and said supplemental presser having upper-margin feed-movements taking place during the return movements of the presser.
